AIR CONDITIONING APPARATUS

Martin G. Terson, Louisville, Ky.

Application May 2, 1933, Serial No. 668,973
Renewed September 17, 1934

7 Claims. (Cl. 257—8)

This invention relates to improvements in heating, cooling and humidifying apparatus.

The general object of the invention is to provide novel means for automatically maintaining the temperature and humidity of a building.

A more specific object of the invention is to provide novel means for heating and humidifying a building.

Another object of the invention is to provide means for cooling and dehumidifying a building.

A further object of the invention is to provide novel means for heating and cooling a building and for simultaneously humidifying and dehumidifying the air in a building.

An additional object of the invention is to provide novel control means for operating air conditioning apparatus.

Another object of the invention is to provide a novel heat exchange apparatus for use in the rooms of a dwelling.

Other objects and the advantages of this invention will be apparent from the following description taken in connection with the accompanying drawings wherein:

Fig. 1 is a fragmentary sectional elevation of a building showing an operative installation of my improved heating, cooling and humidifying apparatus;

Fig. 2 is a side elevation of the humidity controlling device;

Fig. 3 is an enlarged sectional view of an air intake device used in combination with my system;

Fig. 4 is a front elevation of a radiation or heat exchange device used in combination with my system with portions thereof broken away;

Fig. 5 is a section taken on line 5—5 of Fig. 4, and

Fig. 6 is a diagrammatic view showing the wiring of my system.

Referring to the drawings by reference characters I have indicated a building generally at 10 which is shown as including a basement section 12 and a dwelling portion 13. In the basement I provide a steam or hot water heater 14 which is shown as an oil heater and including a blower 15 which is operated by an electric motor 16. Extending from the heater 14 I have shown the usual feed pipe line 17 which extends to various portions of the building and a return pipe line 18 which returns the steam or hot water to the heater 14.

In the pipe 17 adjacent its exit from the heater I provide a three way valve 19 and adjacent the entrance of the return pipe 18 into the heater

the return pipe has a three way valve 20 interposed therein.

In various portions of the building I provide radiation devices such as indicated at 21 in Fig. 1 and shown in detail in Figs. 4 and 5. As shown each radiation device 21 includes a housing 22 which is preferably positioned in a recess provided for the purpose in the wall of the building. The housing 22 is shown as mounted on a base 23 and includes an open front which is preferably closed by a closure member 24 having a screened opening 25 therein. Mounted on the base 23 within the housing 22 I provide a radiator 26 which may be of any standard type including an inlet pipe 27 and an outlet pipe 28. The inlet pipe 27 preferably has a control valve 29 interposed therein.

As shown in Fig. 1 the radiator inlet pipe 27 communicates with the feed pipe 17 and the radiator outlet pipe 28 communicates with the return pipe 18.

In the housing 22 at the rear of the radiator 26 I provide an air chamber 30 which is formed by a partition 31 having an opening 31' therethrough of approximately the same size as that of the radiation portion of the radiator.

Mounted in the housing 22 to the front of the radiator I provide a shutter device 32 which may be of any standard type including pivoted horizontal fin members 33 which are actuated by an operating handle 34.

Positioned in an aperture 35 in the floor of the building I provide an air intake member indicated generally at 36 and shown in detail in Fig. 3. As shown the device 36 includes a housing 37 having an open top which is closed by a grilled member 38 through which air is adapted to pass into the housing 37. The housing 37 further includes an outlet conduit 39. In the basement of the building I provide an air conditioning device 40, a blower device 41 and a refrigerating device 42.

As shown the air conditioning device 40 comprises a housing 43 having therein an air cleaning chamber 44, an air humidifying chamber 45 which may include a humidifier of the water spray type and an air dehumidifying chamber 46 which may contain a de-humidifier of the type wherein moisture is condensed on cooling coils. At one side thereof the device 40 includes a passageway 47 communicating at its upper end with the cleaning chamber 44 and at its lower end with the dehumidifying chamber 46. The humidifying chamber 45 includes an entrance passageway 48 which communicates with the passageway 47.

intermediate the length thereof. Adjacent the upper end of the passageway 47 I provide a valve member 49 which when open as shown in Fig. 1 allows free passage from the cleaning chamber 44 into the passageway 47 and when closed restricts passage from the chamber 44 into the passageway 47. The valve member 49 is mounted on a pivoted shaft 50 which extends out through one side of the housing 43 where an operating arm 51 is secured thereto (see Fig. 2).

Adjacent the entrance passageway 48 of the humidifying chamber 45 I provide a valve member 52 which when it is in a closed position as shown in Fig. 1 restricts passage through the passageway 47 and directs air through the entrance passageway 48 of the humidifying chamber 45. When the valve member 52 is open it allows free passage through the passageway 47 and restricts passage through the entrance passageway 48 of the humidifying chamber 45. The valve member 52 is mounted on a pivoted shaft 53 which extends through one side of the housing 43 where an operating arm 54 is secured thereto (see Fig. 2).

At the side of the device 40 opposite the passageway 47 the device 40 includes a passageway 55 which at its upper end communicates with the cleaning chamber 44 and at its lower end communicates with an exit conduit 56.

Adjacent the upper end of the passageway 55 I provide a valve member 57 which when closed as shown in Fig. 1 restricts passage from the cleaning chamber 44 into the passageway and when open allows free passage from the chamber 44 into the passageway 55.

The valve 57 is mounted on a pivoted shaft 58 which extends through one side of the housing where an operating arm 59 is secured thereto (see Fig. 2).

The dehumidifying chamber 46 includes an outlet passageway 60 which communicates with the passageway 55. Passage through the passageway 60 is shown as controlled by a movable shutter device 61 which includes an operating rod 62 which extends through one side of the housing where it is slackly connected to a pivoted operating arm 63 (see Fig. 2).

The dehumidifying chamber 46 includes an outlet passageway 64 which communicates with the passageway 55. Adjacent the dehumidifying outlet 64 I provide a valve member 65 which when closed as shown in Fig. 1 restricts passage through the passageway 64 into the passageway 55 and when open allows free passage from the dehumidifying chamber 46 through the outlet 64 thereof into the passageway 55. The valve member 65 is mounted on a pivoted shaft 66 which extends through one side of the housing 43 where an operating arm 67 is secured thereto (see Fig. 2).

The operating arm 51 of the valve member 49 and the operating arm 59 of the valve member 57 are connected by a bar 68. As shown in Fig. 6, the bar 68 passes through a pair of solenoid coils 69 and 70 and includes solenoid core portions 71 and 72. Carried by the bar 68 I provide an arm which includes contact bar portion 73 and 74. The contact bar 73 is adapted to bridge a pair of contact tracks 75 and 76 and the contact bar 74 is adapted to bridge a pair of contact tracks 77 and 78.

The operating arm 54 of the valve member 52 and the operating arm 67 of the valve member 65 are connected by a bar 79. As shown in Fig. 6 the bar 79 like the bar 68 passes through a pair

of solenoid coils 80 and 81 and includes solenoid core portions 82 and 83. Carried by the bar 79 I provide an arm which includes a pair of contact bar portions 84 and 85. The contact bar 84 is adapted to bridge a pair of contact tracks 86 and 87 and the contact bar 85 is adapted to bridge a pair of contact tracks 88 and 89.

The operating arm 63 of the shutter device 61 is slackly connected to a bar 90 which like the bars 68 and 79 passes through a pair of solenoid coils 91 and 92 and includes solenoid core portions 93 and 94. Carried by the bar 90 I provide an arm which includes a pair of contact bar portions 94 and 95. The contact bar 94 is adapted to bridge a pair of contact tracks 96 and 97 and the contact bar 95 is adapted to bridge a pair of contact tracks 98 and 99.

The operating arm 59 is adapted to be retained in the position to which it is moved by a past center spring 100 and the operating arm 54 is adapted to be retained in a position to which it is moved by a similar spring 101 and the operating arm 63 is adapted to be retained in a position to which it is moved by a similar spring 102 (see Fig. 2).

The blower device 41 includes a housing 103 having an outlet 104. The conduit 56 from the device 40 communicates with the interior of the housing 103 adjacent the lower end thereof. Positioned in the housing 103 intermediate the conduit 56 and the outlet 104 I provide a fan 106 which is mounted on a shaft 107 connected to the armature shaft 108 of an electric motor 109. The fan 106 is adapted to draw air from the conduit 56 and discharge it out through the outlet 104 into an air conduit 110 which conveys the air to different portions of the building.

The radiator device 21 includes an inlet conduit 112 which communicates with the air conduit 110 at one end and opens into the air chamber 30 at the opposite end. The passageway from the inlet conduit 112 into the air chamber 30 is controlled by a pivoted valve member 113 which includes an operating rod 114.

The outlet conduit 39 of the air intake device 36 communicates with an air return conduit 115 which communicates with the air cleaning chamber 44 of the air conditioning device 40.

Thus when the motor 109 is operating the fan 106 draws air from the air return conduit 115 into the conditioning device 40 then therefrom through the conduit 56 into the housing 103 and then discharges it therefrom into the air conduit 110 from whence it passes through the conduit 112 into the air chamber 30 of the device 21 and thence through the opening 31' and past the radiator 26, through the shutter device 33 and out through the screened opening 25 into the room.

The refrigerating device 42 may be of any desired type and forms no part of my invention. As shown the device 42 includes a housing 116 in which a rotary compressor 117 driven by an electric motor 118 is positioned. Also, positioned in a portion of the housing I provide a condenser 119. The outlet end of the compressor 117 is connected by a delivery conduit 122 to the condenser 119 which is in turn connected to the three-way valve 19, by a conduit 121 and the three-way valve 20 is connected by a return conduit to the inlet end of the compressor 117.

The three-way valve 19 includes an operating arm 123 and the three-way valve 20 includes an operating arm 124. The operating arms 123 and 124 are adapted to be retained in a position to which they have been moved by past center

5 springs 125. The operating arm 123 of the valve 19 and the operating arm 124 of the valve 20 are connected by a bar 126. As shown in Fig. 6 the bar 126 passes through a pair of solenoid coils 129 and 130. Carried by the bar 126 I provide 10 an arm which includes a pair of spaced contact bar portions 131 and 132. The contact bar 131 is adapted to bridge a pair of contact tracks 133 and 134 and the contact bar 132 is adapted to bridge a pair of contact tracks 135 and 136.

10 When the three-way valves 19 and 20 are open as shown in Fig. 1, the valve 19 restricts communication between the pipe 120 and the pipe 17 and between the pipe 121 and the pipe 18 and directs steam or hot water from the heater 14 into the feed pipe 17 from whence it passes through the pipe 27 into the radiator 26 and thence therefrom through the outlet pipe 28 15 into the return pipe 18 from which it is directed by the valve 20 into the heater 14. When the valves 19 and 20 are closed they restrict communication between the heater and the pipes 17 and 18 and allow communication between the pipes 17 and 18 and the pipes 120 and 121. Thus 20 when the motor 118 operates the compressor 117 refrigeration fluid is forced through the pipe 120 and is directed by the valve 19 into the feed pipe 17 thence through the inlet pipe 27 into the radiator 26 and then therefrom through the outlet pipe 28 into the return pipe 18 from which the valve 20 directs it into the return pipe 121.

25 From the foregoing it will be apparent that when the blower 41 is operating air passing from the chamber 30 past the radiator 26 will be either heated or cooled depending on whether the heater 14 or the refrigerating device 42 is operating.

30 By actuating the operating handle 34 of the shutter device 32 the fins 33 thereof may be positioned to direct the air upward, downward or horizontally to suit the desire of the operator. By actuating the valve 113, the volume of air entering the chamber 30 may be controlled and by actuating the control valve 29 the degree of radiation from the radiator 26 may be controlled.

35 When the valves 52, 57 and 65 of the air conditioning device 40 are closed and the valve 49 is open as shown in Fig. 1 the air passing through the device 40 after being cleaned in the cleaning chamber 44 passes through the humidifying chamber 45 where moisture is mixed with the air before it passes therefrom through the exit passageway 60 into the passageway 55.

40 When the valve 57 is closed and the valve 49 45 and 65 are open and the valve 52 is actuated to restrict passage through the passageway 48 into the humidifying chamber 45, the air passing through the device 40 after being cleaned in the cleaning chamber 44 passes through the passageway 47 into and through the de-humidifying chamber 46 wherein the moisture in the air is extracted therefrom.

45 When the valve 49 is closed and the valve 57 is open air passing through the device 40 after being cleaned in the cleaning chamber 44 passes into the passageway 55 and thence through the conduit 56 into the device 41 without being either humidified or de-humidified. The operation of the heater and the refrigerating device is automatically controlled by a thermo-responsive device 140 while the operation of the air conditioning device is controlled by a humidity operated device 141.

50 As shown in Fig. 6 the thermo device 140 includes a rheostat winding 142 which is engaged

5 by the free end of a thermo-responsive arm 143. Adjacent the arm 143 I provide a contact arm 144 which is pivotally mounted adjacent one end as at 145 and adjacent the opposite end includes an arcuate portion 146 which is engaged by the 10 thermo-responsive arm 143. The device 140 further includes a control switch indicated generally at 147 which includes pivoted contact bars 148, 149 and 150. The contact 148 is adapted in one position to engage a contact 151, the contact bar 149 is adapted in one position to engage a contact 152, and in another position to engage a contact 153, and the contact arm 150 is adapted in one position to engage a contact 154. The contact bars 148, 149 and 150 are suitably connected by 15 a bar 155 so that when the contact bar 148 engages its associated contact 151 the contact bar 149 will engage its associated contact 152 and be out of engagement with the contact 153 and the contact bar 150 will be out of engagement with 20 its associated contact 154. When the contact bar 25 engages its associated contact 154 the contact bar 148 swings out of engagement with its associated contact 151 and the contact bar 149 swings out of engagement with its associated contact 152 and engages the contact 153.

20 The humidity control device 141 includes an arcuately movable arm 156 having contact bar portions 157 and 158. The contact bar 157 in one extreme position engages a contact 159 and in 30 the other extreme position engages a contact 160 while in an intermediate position it engages a contact track 161'. In all positions of the arm 156 the contact arm 158 engages a contact track 162. When the arm 156 is in an intermediate position the contact bar 158 is adapted to bridge between the contact track 162 and a contact 163, and when the contact bar 157 bridges between the contact 160 and the contact track 161' the contact arm 158 bridges between the contact track 40 162 and a contact 163'.

35 The device 141 further includes a pivoted switch arm 164 which in one position engages a contact 165 and in another position engages a contact 166. The contact arm 144 of the device 45 140 is connected by a wire 167 to one side of source of electricity shown as a line wire 168. One end of the rheostat coil 142 is connected by a wire 169 to the contact 151 and the opposite end of the rheostat coil is connected by a wire 170 to the contacts 154 and 153. The contact 152 is connected by a wire 171 to the wire 169. The contact 153 is connected by a wire 171 to the wire 169. The contact arm 148 is connected by a wire 172 to one terminal of the heater motor 16 while 50 the other terminal thereof is connected by a wire 173 to the other side of a source of electricity shown as line wire 174. Thus when the contact bar 148 engages the contact 151 current flows from the line wire 168 through the wire 167 to 55 the contact arm 144 and thence through the thermo-responsive arm 143 to the rheostat coil 142 and through the wire 169 to the contact 151. Then through the contact bar 148 and the wire 172 to the motor 16 and returns to the line wire 60 174 through the wire 173 thereby operating the motor 16.

65 As the temperature rises the thermo-responsive arm 143 moves in the direction of the arrow thereby decreasing the supply of current to the motor 16 whereupon the motor operates 70 at a decreased speed and when the thermo-responsive arm 143 moves out of engagement with the arcuate section 146 of the contact arm 144 the circuit to the motor 16 is broken whereupon the motor ceases to operate. As the temperature 75

drops the thermo-responsive arm 143 moves into engagement with the portion 146 of the contact arm 144 whereupon a circuit is again established to the motor 16.

5 The contact bar 149 is connected by a wire 175 to one terminal of the blower motor 109 while the other terminal thereof is connected by a wire 176 to the wire 173. Thus when the contact bar 149 engages the contact 152 current flows from the 10 rheostat coil 142 through the wire 171 to the contact 152 thence through the contact bar 149 and the wire 175 to the blower motor 109 and returns to the line wire through the wire 176.

For operating the blower motor 109 independent 15 of the device 140 I provide a pivoted switch 177 which in a closed position engages a contact 178. The contact 178 is connected by a wire 179 to the line wire 168 and the switch bar 177 is connected by a wire 180 to the wire 175. Thus 20 when the switch bar 177 engages the contact 178 current from the line wire 168 is directed to the motor 109 independent of the position of the elements of the device 140. A switch 177' is opened to prevent feedback to the motor 16 through the switch 149.

25 To operate the refrigerating unit, the switch 147 is operated to swing the contact bar 148 out of engagement with the contact 151, the contact bar 149 swings out of engagement with the contact 152 and into engagement with the contact 153 and the contact bar 150 swings into engagement with the contact 154. The contact arm 144 is then swung to the other side of its pivoted point as indicated by the dotted lines in which 30 position when the temperature rises the arm 143 moves into engagement with the arcuate portion 146 and when the temperature drops swings out of engagement with the portion 146.

When the device 140 is thus set current flows 35 from the line wire 168 through the wire 167 to the contact arm 144 and thence through the contact arm 143 to the rheostat coil 142. From the coil 142 the current flows through the wire 170 to the contacts 154 and 153. From the contact 40 154 the current flows through the contact bar 150 and a wire 181 to one terminal of the refrigerator motor 118 and from the other terminal thereof it returns to the line wire 174 through wires 182 and 176. At the same time current flows from 45 the contact 153 through the contact bar 149 and the wire 175 to the blower motor 109 and returns therefrom to the line wire 174 through the wire 176. One end of the solenoid coil 128 is connected by a wire 183 to the line wire 174 while 50 the opposite end is connected by a wire 184 to the contact track 136. The associated contact track 135 is connected by a wire 185 to the wire 172. Thus when the contact bar 132 bridges the contact tracks 135 and 136 and current is 55 directed to the heater motor 16 through the wire 172 and current flows through the wire 185 to the contact track 135 thence through the contact bar 132 to the contact track 136 and then through the wire 184 to the solenoid coil 128 through the coil and returns to the line wire 174 through the wire 183 thereby energizing the solenoid coil 128. When the coil 128 is thus energized it attracts 60 the core portion 129 of the bar 126 thereto thereby swinging the operating arms of the valves 19 and 20 to a position to allow the pipes 17 and 18 to communicate with the heater 14 as shown in Fig. 1. When the valve arms swing past center the springs 125 associated therewith pull the arms and bar in the direction in which they are moving. As the bar 126 is moved the contact bar 65

132 moves out of engagement with the contact tracks 135 and 136 and the contact bar 131 moves into engagement with the contact tracks 133 and 134.

One end of the solenoid coil 127 is connected 5 by a wire 186 to the line wire 174 and the opposite end of the coil is connected by a wire 187 to the contact track 134 while the companion contact track 133 is connected by a wire 188 to the wire 181. When the switch 147 is actuated to operate the refrigerating device and current flows to the refrigerator motor 118 through the wire 181 current also flows through the wire 188 to the contact track 133 then through the contact bar 131 to the contact track 134 and thence through the wire 187 to the coil 127, through the coil and returns to the line wire 174 through the wire 186 thereby energizing the solenoid coil 127. When the solenoid coil 127 is thus energized it attracts the core portion 129 20 of the bar 126 thereto thus moving the bar 126 which swings the operating arms of the valves 19 and 20 to a position to restrict communication between the pipes 17 and 18 and the heater and allows communication between the pipes 17 and 25 18 and the refrigerator pipes 120 and 121. When the valve arms swing past center the springs 125 continue to move the bar 126 which moves the contact bar 131 out of engagement with the contact tracks 133 and 134 and moves the contact bar 132 into engagement with the contact tracks 30 135 and 136.

One end of the solenoid coil 40 of the air conditioning device is connected by a wire 190 to the line wire 174 and the opposite end of the coil is 35 connected by a wire 191 to the contact track 78. The companion contact track 77 is connected by a wire 192 to the contact 159 of the device 141 and by a wire 193 to the contact 161, and by a wire 193' to the contact 163'. The contact track 40 161' is connected by a wire 194 to the contact 165 and the contact bar 164 is connected by a wire 195 to the line wire 168. One end of the solenoid coil 69 is connected by a wire 196 to the wire 190 and the opposite end of the coil is 45 connected by a wire 197 to the contact track 78 while the companion contact track 75 is connected by a wire 198 to the contact 166.

When it is desired to operate the air conditioning device 40 automatically the switch bar 164 is 50 moved into engagement with the contact 165 whereupon current is directed from the line wire 168 through the wire 195, the contact bar 164, the contact 165 and the wire 194 to the contact track 161'. 55

When the air is dry the humidity operated device 141 swings the operating arm 156 thereof upward to a position wherein the contact bar section 157 thereof bridges the contact track 161' and the contact 159. When the air is humidified 60 to a predetermined degree the device 141 swings the arm 156 thereof downward to an intermediate position wherein the contact bar section 157 thereof bridges between the contact track 161' and the contact 161 and the contact bar 65 section 158 bridges between the contact 163 and the contact track 162. When the air is exceedingly humid the device 141 moves the operating arm 156 thereof to a lowered position wherein the contact bar section 157 thereof bridges between the contact track 161' and the contact 163. When the air is 70 extremely humid the device 141 moves the operating arm 156 thereof to a lowered position wherein the contact bar section 157 thereof bridges between the contact track 162 and the contact 163'.

When the switch bar 164 engages the contact 165 and the contact bar section 157 of the op- 75

erating arm 156 bridges between the contact track 161' and the contact 159 current is directed through the wire 192, the contact track 77, contact bar 74, the contact track 78 and the wire 191 to the solenoid coil 70 and thence through the wire 190 to the line wire 174 thereby energizing the coil 70. When the solenoid coil 70 is thus energized it attracts the core portion 72 of the bar 68 thereto thereby moving the bar 68 which in turn swings the operating arms 51 and 59 to a position wherein the valve 49 allows communication between the cleaning chamber 44 and the passageway 47. When the valves 49 and 57 are in this position the air is directed into the passageway 47 whence it passes either into the humidifying chamber 45 or the dehumidifying chamber 46 depending on the position of the valve 52.

When it is desired to direct the air directly from the cleaning chamber 44 into the passageway 55 the switch bar 164 is moved into engagement with the contact 166 whereupon current is directed to the coil 69 through the wire 195, switch bar 164, contact 166, wire 198, contact track 75, contact bar 73 and the wire 197 and from the coil 69 to the line wire 174 through the wires 196 and 190 thereby energizing the coil 69. When the solenoid coil 69 is thus energized it attracts the core portion 71 of the bar 68 thereto thereby moving the bar 68 which in turn swings the operating arms 51 and 59 to a position wherein the valve 49 restricts passage between the cleaning chamber 44 and the passageway 47 and wherein the valve 57 allows free passage between the cleaning chamber 44 and the passageway 55.

One end of the solenoid coil 91 is connected by a wire 200 to the wire 182 and the other end of the coil 91 is connected by a wire 201 to the contact track 97 while the companion contact track 96 is connected by a wire 202 to the contact 163. One end of the solenoid coil 92 is connected by a wire 203 to the wire 200 while the opposite end of the coil 92 is connected by a wire 204 to the contact track 99. The companion contact track 98 is connected by a wire 205 to a contact 206 which is engaged by the contact bar 158 of the arm 156 when the arm 156 is in a raised position. When the contact bar 158 bridges between the contact track 162 and the contact 206 current is directed from the contact track 162 to the solenoid coil 92 through the contact 206, the wire 205, contact track 98, contact bar 95, contact track 99 and the wire 204 and returns to the line wire 174 through the wire 203 thereby energizing the solenoid coil 92. When the coil 92 is thus energized it attracts the core portion 94 of the bar 90 thereto thereby moving the bar 90 which in turn swings the shutter operating arm 63 to a position wherein the shutter device 61 partly restricts the passage of air from the humidifying chamber 45 thru the exit 60 into the passageway 55. When the passage of air is thus restricted the air becomes more saturated with moisture in the humidifying chamber before passing therefrom.

When the operating arm 156 of the device 141 is in an intermediate position and the contact bar portion 158 thereof bridges between the contact track 162 and the contact 163 current is directed to the solenoid coil 91 from the contact track 162 through the contact 163, the wire 202, contact track 96, contact bar 94, contact track 97 and the wire 204 and returns to the line wire 174 through the wire 192 thereby energizing the solenoid coil 92. When the solenoid coil 92 is thus energized

it attracts the core portion 93 of the bar 90 thereto thereby moving the bar 90 which in turn swings the shutter operating arm 63 to a position wherein the shutter device 61 allows free passage through the exit passageway 60.

One end of the solenoid coil 80 is connected by a wire 208 to the wire 176 and the opposite end of the coil 80 is connected by a wire 209 to the contact track 87 while the companion contact track 86 is connected by a wire 210 to the wire 191, and a wire 210' bridges between the wires 202 and the wire 210. One end of the solenoid coil 81 is connected by a wire 212 to the wire 208 and the other end of the coil is connected by a wire 213 to the contact track 89 while the companion contact track 88 is connected by a wire 214 to the contact 160.

When the current is directed through the wire 191 to the solenoid coil 70 current is also directed to the solenoid coil 80 through the wire 210, the contact track 86, contact bar 84, contact track 87 and the wire 209 and returns to the line wire 174 through the wire 208 thereby energizing the coil 80. When the coil 80 is thus energized it attracts the core portion 82 of the bar 79 thereto thereby moving the bar 79 which in turn swings the control arms 54 and 67 to a position wherein the valve 52 allows free passage through the entrance passageway 48 from the cleaning chamber 44 to the humidifying chamber 45 and restricts passage through the passageway 47 to the dehumidifying chamber 46 and wherein the valve 65 restricts passage through the exit passageway 64 of the de-humidifying chamber 46. Furthermore, when current is directed through the wire 202 to the solenoid coil 91 current is also directed through the wire 210' to the solenoid coil 80. Thus each time the coil 91 is energized to open the shutter device 61 the coil 80 is energized to close the valves 52 and 65. When the operating arm 156 of the device moves to its lowermost position and the contact bar portion 157 thereof bridges between the contact track 161' and the contact 160 current is directed to the solenoid coil 81 from the contact track 161' through the contact bar 157, contact 160, wire 214, contact track 88, contact bar 85, contact track 89 and the wire 213 and returns to the line wire 174 through the wire 212 thereby energizing the coil 81. When the solenoid coil 81 is thus energized it attracts the core portion 83 of the bar 79 thereto and moves the bar 79 which in turn swings the operating arms 54 and 67 to positions wherein the valve 52 allows free passage through the passageway 47 from the cleaning chamber 44 to the de-humidifying chamber 46 and restricts passage through the entrance passageway 48 of the humidifying chamber 45 and wherein the valve 65 allows free passage through the exit passageway 64 of the de-humidifying chamber 46. When the contact bar 157 bridges between the contact track 161' and the contact 160 the contact bar 158 bridges between the contact track 162 and the contact 163' the wire 193' and the wire 192 to the contact track 77 which will energize the solenoid coil 70 should the valve 49 be in a closed position and the valve 57 in an open position.

From the foregoing it will be apparent that when the switch 147 is set to operate the heater 14, the blower 41 will also operate and as the temperature rises the action of both the heater and the blower will slow down until the temperature rises a predetermined degree where-

upon the operation of the heater and the blower will cease.

When the switch 147 is set to operate the refrigeration device 42 the blower 41 will also operate and as the temperature drops the action of both the refrigeration device and the blower will slow down until the temperature falls below a predetermined degree whereupon the operation of the refrigeration device and the blower will cease.

It will also be seen that when the switch bar 144 engages the contact 165 and the air is dry the air conditioning device 40 will be automatically operated to humidify the air as it passes therethrough and when the air contains a predetermined amount of moisture the shutter device 61 will be automatically operated to allow free passage of air through the humidifying chamber 45 whereupon the air will collect less moisture as it passes through the chamber 45. When the air contains a predetermined excessive amount of moisture the air conditioning device 40 will be automatically operated to de-humidify the air passing therethrough.

When the summer season approaches the operator causes the heating apparatus to stop operating. He then drains the water out of the conduits. After this is done the valves 19 and 20 are operated to cut off the heating plant from the circulating system and to turn the cooling plant into the circulating system.

The plant thus operates until the fall season approaches. At this time the cooling apparatus is stopped and the cooling fluid is allowed to pass from the circulating system.

The valves 19 and 20 are then operated and the heating plant is started.

From the foregoing description it will be apparent that I have provided a novel heating and cooling and air conditioning system for buildings which is simple in construction and highly efficient in operation.

Having thus described my invention, I claim:

1. In an air conditioning apparatus, a heat exchange device, a heating means, a cooling means, means to selectively at will cause said heat exchange device to be heated or cooled by said heating or cooling means, means to pass air over said exchange device and means to change the condition of the air before it passes over the heat exchange device, said air conditioning means including an air cleaner, an air humidifier, and an air de-humidifier, means to control the flow of air through said air cleaner, means to control the flow of air through said humidifier, means to control the flow of air through said de-humidifier, a thermostatic means to control the operation of said heating means and said cooling means, electromagnetic means to control the operation of said air cleaning means, electromagnetic means to control the operation of said humidifying means, electromagnetic means to control the operation of said de-humidifying means, and means adjacent said heat exchange device to control the amount of air passing therover.

2. In an air conditioning apparatus, a heat exchange device therein, means operable to heat said device, means to cool said device, air conditioning means remote from said device to change the state of a volume of air, said air conditioning means including an air cleaner, a humidifier and a de-humidifier, means to control said air cleaner, means to control said humidifier, means to control said de-humidifier and means to direct

air from said last means through said exchange device into the building.

3. In an air conditioning apparatus, a heat exchange device, a heating means, a cooling means, means to selectively at will cause said heat exchange device to be heated or cooled by said heating or cooling means, means to pass air over said exchange device and means to change the condition of the air before it passes over the heat exchange device, said air conditioning means including an air cleaner, an air humidifier, and an air de-humidifier, means to control the flow of air through said air cleaner, means to control the flow of air through said humidifier, a thermostatic means to control the operation of said heating means and said cooling means, and means adjacent said heat exchange device to control the amount of air passing therover.

4. In an air conditioning apparatus, a central heating means, a central cooling means, a plurality of heat exchange devices remote from said central means, return circuit conduits selectively connecting said heating and cooling means and said heat exchange devices whereby on operation of the heating plant the heat exchange devices will be heated and on operation of said cooling plant the heat exchange devices will be cooled, means to blow air over said heat exchange devices whereby the temperature of the air will be varied according to the thermal condition of the heat exchange devices, air humidifying and de-humidifying means in the air stream to vary the moisture content of the air, and means to control the operation of the heating and cooling means.

5. In an air conditioning apparatus, a central heating and cooling plant, a plurality of heat exchange devices remote from said central heating and cooling plant, return circuit conduits selectively connecting said central heating and cooling plant and each of said heat exchange devices whereby on operation of the heating plant the heat exchange devices will be heated and on operation of said cooling plant the heat exchange devices will be cooled, a chamber adjacent each of said heat exchange devices and communicating therewith, air blower apparatus at said heating cooling plant and remote from said heat exchange devices, a conduit connecting said air blower apparatus with each of said chambers whereby when said air blower apparatus is operated air will be blown through said chambers and over said heat exchange devices whereby the temperature of the air will be varied according to the thermal condition of the heat exchange devices, air humidifying and de-humidifying means adjacent said blower apparatus and communicating with said blower apparatus to vary the moisture content of the air, and means to control the operation of the heating and cooling plant.

6. In an air conditioning apparatus, a central heating, a cooling plant, a plurality of heat exchange devices remote from said central heating and cooling plant, a feed conduit connecting said heating plant and said cooling plant to the head exchange devices, a return conduit connecting said heat exchange devices to the heating plant and the cooling plant, selective central means whereby on operation of the heating plant the heat exchange devices will be heated and on operation of said cooling plant the heat exchange devices will be cooled, a chamber adjacent each of said heat exchange devices and communicating therewith, air blower apparatus at said heating

and cooling plant and remote from said heat exchange devices, a conduit connecting said air blower apparatus with each of said chambers whereby when said air blower apparatus is operated air will be blown through said chambers and over said heat exchange devices whereby the temperature of the air will be varied according to the thermal condition of the heat exchange devices, air humidifying and de-humidifying means adjacent said blower apparatus and communicating with said blower apparatus to vary the moisture content of the air, and means to control the operation of the heating and cooling plant.

5. In an air conditioning apparatus, a central heating means, a central cooling means, a plurality of heat exchange devices remote from said central means, return circuit conduits selectively connecting said heating and cooling means and said heat exchange devices whereby on operation 10 of the heating plant the heat exchange devices

will be heated and on operation of the cooling plant the heat exchange devices will be cooled, a single means remote from said heat exchange devices to blow air over all of said heat exchange devices when the latter are heated to vary the temperature of the air according to the thermal condition of the heat exchange devices, said air blowing means being also effective to blow air over the heat exchange devices when the latter are cooled to thereby both cool and de-humidify the air, an 15 air supply conduit, an air cleaner in communication with said air supply conduit, a humidifier, valved means affording communication between the air cleaner and the humidifier, valve means affording communication between the humidifier 20 and the blowing means and valved means affording direct communication between the air cleaner and the blowing means, and means to control the operation of the heating and cooling means.

MARTIN G. TORSON. 20
